APPARATUS FOR MOLDING CARAMELS AND
LIKE CUT-UP PLASTIC MATERIALAlfred German Rose, Lincoln, England, assignor
to Rose Brothers (Gainsborough) Limited,
Gainsborough, England, a British companyApplication April 5, 1932, Serial No. 603,367, and
in Great Britain April 23, 1931

5 Claims. (Cl. 107—4)

This invention relates to machines for wrapping caramels or the like and is concerned with machines of the class having a knife or other cutting device by which a bar of plastic stock is cut to form caramels, and caramel-wrapping mechanism to which each caramel cut is delivered and by which it is wrapped. In such machines difficulty has been found in ensuring that the machine shall produce caramels of uniform 3 shape which can be wrapped to form correctly and proportioned and regularly shaped packages. It is the object of this invention to provide a machine in which this difficulty is overcome.

According to the present invention a caramel-wrapping machine of the class set forth above is provided with a molding device which is located between the cutting device and the wrapping mechanism and is arranged to receive each 10 caramel cut and mold it to a definite shape before it is wrapped. Preferably, the molding device comprises a mold-box which is open at one end and a reciprocating plunger which is arranged to feed caramels one by one into the 15 mold-box and to constitute a movable wall of the mold-box by which molding pressure is applied to the caramel in the box. The mold-box may be formed with two movable walls opposite one another and means for moving said 20 walls after each molding operation, to open the box temporarily on two opposite sides, and there is provided an additional reciprocating plunger arranged to move, at right angles to the path of the first plunger, through one of said openings 25 and eject the molded caramel through the opposite opening to the wrapping mechanism.

A caramel-wrapping machine embodying the above and other features of the present invention will now be described by way of example only 30 with reference to the accompany drawings, in which:—

Figure 1 is a plan showing cutting and molding mechanism employed in the machine, certain parts being omitted for sake of clearness, 35 and

Figures 2, 3 and 4 are vertical cross-sections through the mechanism shown in Figure 1 on the lines 2—2, 3—3 and 4—4 respectively of that figure.

Like reference numerals indicate like parts in all the figures of the drawings.

The invention has been illustrated by way of example as applied to a machine of the known kind in which a succession of caramels are severed from a bar of plastic stock and are fed one

by one, each with a wrapper, into a receiving pocket in an intermittently rotated pocket-wheel. As each caramel and its wrapper is moved into a pocket the wrapper is rotated round three sides of the caramel. The pocket-wheel then rotates intermittently to carry the caramel and its wrapper to suitable folding and/or twisting mechanism which completes the enclosure of the caramel.

The machine is provided with a pair of intermittently rotated feed rollers 10, 10 (Figures 1 and 3) which feed a bar of stock from left to right (Figure 1) to a cutting station. The rollers bring the stock to rest with its end resting on a supporting platform 11. While the bar of stock is at rest, a caramel is cut off by a constantly rotating eccentric knife 12. The cut caramel is then fed by a reciprocating plunger 13 into the position shown in chain lines in Figure 1 in which it lies in a channel 14.

The plunger 13 is supported intermediate its ends on the top of a lever 15 (Figure 3) and at its front end on a lever 16 which is pivoted on the machine frame at 17. The lever 15 is pivoted at 18 at one end of a two-armed lever 19 which is pivoted on the machine frame at 20. The lever 19 carries a roller held in engagement with a cam 22 by a spring 23. The lever 15 is secured to a lever 24 which is connected by a rod 25 to a strap 26 mounted on an eccentric 27. The cam 22 and eccentric 27 are mounted on a constantly rotating shaft 28. As the eccentric 27 rotates it rocks the levers 24 and 15 and thus reciprocates the plunger 13. While the plunger 13 is moving from left to right (Figure 3) the lever 19 is held 75 in the position shown in which its roller cooperates with a portion 22a of the cam 22. When the plunger reaches its extreme right-hand position, the roller 21 passes on to a portion 22b of the cam and the lever 19 is rocked by the spring 23 and lowers the lever 15, thus lowering the end of the plunger 13 which passes through a slot 29 in the supporting platform 11 so that the plunger returns below the level of the platform. This allows of the feed rollers being 80 restarted so as to feed the stock forward without waiting until the plunger has returned to its left-hand position.

The channel 14 is formed with a horizontal base 30, two fixed side walls 31, 32 and a top wall 105 33. The top wall 33 has been omitted from Figure 1 for the sake of clearness. The right-hand end (Figure 1) of the channel 14 is closed by a stop piece 34 and the side walls 31 and 32 are cut away to the left of this stop piece so as to 110

- provide openings on the opposite sides of the channel. These openings may be closed by a fork-shaped member having a pair of upstanding parallel wall elements 35 (Figures 2 and 4) joined together at their lower ends and secured to a rod 36. When this member is raised from the position shown, it closes the openings in the side walls of the channel and, together with the base and top of the channel and the stop piece, forms a mold-box for the caramels. The rod 36 is mounted to slide vertically in bearings 37 and 38 and a collar 39 is secured to it. A block 41 is pivoted at one end of a bell-crank lever 42 and is held between two extensions 40 of the collar 39 between which it can slide. The bell-crank 42 is pivoted at 43 and is connected by a rod 44 to a lever 45 which is pivoted at 46 in the machine frame. The lever 45 carries a roller 47 which engages a cam track 48 in a cam 49. The cam 49 is secured to the shaft 28 and the cam track is shaped so that the lever 45 is rocked and rocks the bell-crank lever 42 which in turn raises and lowers the side walls 35 of the mold-box.
- The caramel is pushed into the mold-box by a pusher 50 (Figures 1 and 2) which is mounted at one end on a lever 51 pivoted at 52 and intermediate its ends on a lever 53 pivoted at 54. The lever 53 is connected by a rod 55 to the free end of a lever 56 which is pivoted at 57. This lever carries a roller 58 which engages a track 59 in a cam 60 secured on the shaft 28. The cam 60 is arranged to oscillate the lever 53 and reciprocate the plunger 50 and is so shaped that the plunger dwells when in its extreme left-hand position.
- The caramels after being molded are ejected from the mold-box by a plunger 61 which is pivoted on the upper end of a lever 62. This lever is pivoted at 63 and is pivoted to one end of a rod 64. The other end of this rod is forked and its fork ends 65 engage the opposite sides of a sleeve 66 on the shaft 28 so that this sleeve supports the rod 65 at this end. The rod 64 carries a roller 67 engaging in a cam track 68 of a box cam 69. The cam 69 reciprocates the lever 62 and therefore the plunger 61. The plunger 61 carries a roller 70 engaged with a cam track 71 formed in a bearing 73 for the shaft 72 on which the knife 12 is supported. The cam track 72 is so shaped as to cause the operative end of the plunger 61 to move along a straight path.
- The operation of the mechanism will now be described, it being assumed that the parts are initially in the position shown in the drawings, a caramel having been cut off and fed into the channel 14 is shown in Figure 1. The plungers 13 and 61 have reached the end of their movement and are being retracted by their respective cams. Concurrently the plunger 50 is being moved from left to right (Figures 1 and 2) and is moving the caramel into the mold-box. The plunger 61 is fully retracted before the caramel enters the mold-box and the side walls 35 of the mold-box will be raised by the cam 49 acting through the linkage described so that by the time the caramel has been moved fully into the mold-box the side walls 35 will be fully raised, completely enclosing the mold-box. The plunger 50 constitutes a movable wall for the mold-box and at the end of its stroke presses the caramel against the stop piece 34 and applies pressure to the caramel so that the caramel is caused to take the shape of the mold-box.
- The plunger 50 is then retracted by its cam 59 and the side walls 35, which have been held in their upper position by their cam 49 during the molding operation, are moved down until their tops are on a level with or slightly below the top of the base 30. The plunger 61 has meanwhile been held in its retracted position by a concentric portion of its cam 68. As soon as the side walls have fully lowered, the plunger 61 is advanced and passes through the openings provided by the side walls, pushing the caramel into a pocket 75 of the pocket-wheel 76. Prior to the ejection of the caramel from the mold a wrapping paper 77 is fed between the mold and the pocket-wheel 76 and its end is cut off by a suitable knife, not shown, so as to form a wrapper. As the caramel passes into the pocket 75 it carries with it the wrapper which has just been cut off which in a known manner is wrapped round three sides of the caramel.
- During these operations, the feed rollers 10 are feeding the stock forward and the knife 12 will cut off a new caramel. As the plunger 50 reaches the end of its stroke the plunger 13 is raised to its upper position by its cam 22 and is moved forward by the eccentric 27 so as to move the freshly cut caramel into the channel 14. It will be understood that the movements of the plungers 13 and 50 are so timed that the plunger 50 will reach its retracted position before the plunger 13 has moved the caramel into the channel 14 and will dwell in its retracted position until the caramel has been fully moved into the channel 14. As soon as the pocket-wheel 76 has received a caramel it moves one step to carry this caramel to the folding and/or twisting mechanism of the machine and to bring a new pocket 75 opposite the mold-box. This sequence of operations is then repeated.
- I claim:—
1. A caramel-wrapping machine having a cutting device for cutting a bar of stock into separate caramels, a fixed mold-box open at one end, a plunger mounted to reciprocate into and out of the mold-box and mechanisms for feeding each caramel cut into position to be moved by the plunger into the mold box and compressed therein. 115
  2. A caramel-wrapping machine having a cutting device for cutting caramels from a bar of stock, a mold-box open on three of its sides, two opposed walls arranged to close two opposed openings in the mold-box, a reciprocating plunger, mechanism for operating the plunger to move a caramel into the box and mold it therein, mechanism for moving the two walls to open the box on opposite sides temporarily after a caramel has been molded and a second plunger movable through one of the said openings to eject the caramel through the other of the said openings. 125
  3. A caramel-wrapping machine having a cutter for cutting caramels from a bar of stock, a mold-box open at one side and having two opposed movable walls extending at right angles to the open side, two reciprocating plungers, caramel feeding mechanism for moving a caramel cut into the path of one of said plungers, operating mechanism for actuating said plunger to move the caramel into the mold-box and compress it therein, mechanism for moving the said walls to open opposed sides of the box and mechanism for moving the second plunger at right angles to the first plunger through one of the opposed open sides of the box to eject the caramel therefrom. 135
  4. A caramel wrapping machine having a 150

knife for cutting a block of stock into separate caramels, a mold-box open on three sides, a fork-shaped member movable to open and close two opposed open sides of the box, a plunger 5 movable at right angles to said member through the third open side of the box to feed a caramel into said box and mold it therein while the member closes the said opposed open sides, and a second plunger movable at right angles to the 10 first plunger and the fork-shaped member through one of said opposed open sides to eject

a molded caramel through the other opposed open side.

5. A caramel wrapping machine having a cutting device for cutting a bar of stock into separate caramels, a fixed mold-box open at one end, a plunger mounted to reciprocate into and out of the mold-box and arranged to feed each caramel cut into the mold-box and to compress it therein, and mechanism for ejecting each caramel from the mold-box. 80 85
